DESIGN FOR AN AUTOMOBILE HOOD RIDGE ORNAMENT

Calvin L. Furlong, Detroit, Mich.

Application June 15, 1935, Serial No. 57,277

Term of patent 3½ years

To all whom it may concern:

Be it known that I, Calvin L. Furlong, a citizen of the United States, residing at Detroit, in the county of Wayne and State of Michigan, have invented a new, original, and ornamental Design for an Automobile Hood Ridge Ornament, of which the following is a specification, reference being had to the accompanying drawing, forming part thereof.

Fig. 1 is an enlarged perspective view of the automobile hood ridge ornament.

Fig. 2 is an end view taken from the small end of the hood ridge ornament.

Fig. 3 is an end view taken from the large end of the hood ridge ornament.

I claim:

The ornamental design for an automobile hood ridge ornament as shown.

CALVIN L. FURLONG.
